UNITED STATES PATENT OFFICE.

WILHELM S. FERNE, OF PITTSFIELD, MASSACHUSETTS.

AUTOMATIC TYPE-WRITER-OPERATING MECHANISM.

1,115,294.

Specification of Letters Patent.

Patented Oct. 27, 1914.

Application filed February 27, 1914. Serial No. 821,490.

To all whom it may concern:

Be it known that I, WILHELM STEFAN FERNE, a subject of the King of Sweden, residing at Pittsfield, in the county of Berkshire and State of Massachusetts, have invented certain new and useful Improvements in Automatic Type-Writer-Operating Mechanism; and I do hereby declare the following to be a full, clear, and exact description of the invention, such as will enable others skilled in the art to which it appertains to make and use the same.

The primary object of this invention is to provide automatic mechanical means for operating the keys of a typewriter, so that typewritten letters and other papers may be produced in quantities without the labors of a typist.

Another and more specific object of the invention is to provide automatic operating means of this nature, including a perforated strip of paper which is wound from one roll to another, to operate a plurality of levers corresponding in number to the keys of the typewriter, said levers setting into actuation mechanism to drive hammers which depress the keys.

With these and other objects in view as will become more apparent as the description proceeds, the invention consists in certain novel features of construction, combination and arrangement of parts as will be hereinafter more fully described and claimed.

For a complete understanding of my invention, reference is to be had to the following description and accompanying drawings, in which—

Figure 1 is a side elevation of my mechanical operating means, Fig. 2 is a top plan view thereof, and Fig. 3 is a detail of a portion of the mechanism to be herein-after more fully described.

Referring in detail to the drawings by numerals, 1 designates the side plates of a supporting frame of any desired construction, which is arranged in front of the typewriter to be operated, a portion only of the typewriter being illustrated, having the keys 2. A shaft 3 extends transversely between the side plates 1 and supports rigidly a plurality of ratchet disks 4 corresponding in number to the keys of a typewriter. The shaft is continuously revolved in a clockwise direction by any suitable means, such

as a belt 5 driven by a motor 6 and running around a pulley 7 on the shaft 3.

A plurality of hammers 8, corresponding in number to the keys of a typewriter, are supported on the shaft 3 by extending said shaft through transverse openings formed therein, and each hammer is provided on one end with a depending arm 9 which engages the button 10 of one of the keys, as clearly shown in the drawings. Since the keys 2 are held normally in their raised position by the usual typewriter mechanism, they hold the hammers 8 normally in a horizontal plane. Each hammer has pivotally secured to one side adjacent its inner end, a pawl 11 having a tooth engaging arm 12 and a releasing arm 13. When the arm 12 is thrown into engagement with the corresponding ratchet disk 4, the outer end of the hammer will be thrown downwardly to depress one of the typewriter keys. Each pawl is provided centrally of its ends with a tooth 14 having oppositely inclined faces which are alternately engaged by a spring 15, so the pawl may be locked either in its operative or inoperative position.

16 designates an inclined transverse strip extending between the side plates 1 adjacent to the ratchet disks 4 to engage the pawl releasing arm 13 and swing the pawl from engagement with the ratchet teeth so that the depressed key will be released and returned to its raised position.

The pawls 11 are engaged with the teeth of the disks 4 by means of a plurality of levers 17 supported for oscillatory movement on a transverse horizontal shaft. The inner arms 18 of the levers are curved downwardly and inwardly under the inner terminals of the hammers 8, and when swung upwardly a slight distance, come in contact with the teeth engaging arms 12 and pawls 11 to swing said arms in engagement with the teeth of the disks 4.

The action of the levers 17 is controlled by a strip of properly perforated paper 19 which is wound from a spool 20 onto a spool 21. These spools are supported on transverse horizontal shafts having their terminals extended through openings formed in the side plates 1. The roll or spool 21 is driven so as to wind the paper thereon from the spool 20 by a belt 22 from the motor 6 running around a pulley 23. This paper slides across a bar or plate 24 formed with

a series of openings 25 arranged directly under the outer end of the levers 17, and springs 26 connected at their inner ends to the shaft 18 and at their outer ends to said 5 levers to force them toward the openings.

Having described the construction of my automatic or mechanical operating mechanism for typewriters, I will now explain the operation thereof.

- 10 The paper 19 is first perforated, by any desired and suitable means, so as to cause the lever 17 to be operated in proper sequence to insure a similar operation of the typewriter keys. As the paper winds upon 15 the spool 21, the apertures therein register with the openings 25 in the side bar 24, and whenever two such openings come in registration, the corresponding lever 17 is forced thereinto by its spring 26, thus raising 20 the inner end of the lever and bringing it into contact with the corresponding pawl 11. The engagement of the lever 17 with the pawl, swings the tooth engaging arm of the latter into engagement with the teeth 25 of the ratchet disk 3. Since the disk is continuously revolved, the pawl is carried upwardly, swinging the outer end of the hammer 11 downwardly and depressing its key. When the pawl comes in contact with the inclined strip 16, it is swung from locking engagement with the teeth of the ratchet disk and the typewriter key raises, returning the hammer to its normal position ready for 30 the next operation.
- 35 From the foregoing description taken in connection with the accompanying drawings, it will be apparent that I have provided a very simple and practical automatic typewriter operating mechanism which will 40 save the expense of a typist and make it possible to produce at a minimum amount of time and expense, a great number of form letters or printed matter of other natures.

While I have shown and described the 45 preferred embodiment of my invention, it will be understood that minor changes in construction, combination and arrangement of parts may be made without departing

from the spirit and scope of the invention as claimed.

Having thus described my invention, I claim:—

1. In a device of the character described, a horizontal driven shaft, a plurality of toothed disks rigidly secured to said shaft, a 55 plurality of hammers journaled intermediate their ends on the shaft, a pivoted pawl carried by each of said hammers, and means for drawing the pawl into and from locking engagement with the disks. 60

2. In an operating mechanism of the character described, a horizontal driven shaft, a ratchet disk rigidly secured to said shaft; a hammer journaled intermediate its ends on the shaft, a spring pressed pawl carried 65 by the hammer, means for throwing said pawl into locking engagement with the toothed disk, and a stop for swinging said pawl out of engagement with the disk.

3. In a typewriter operating mechanism, 70 a driven shaft, a toothed disk rigidly secured to said shaft, a key engaging hammer journaled intermediate its ends on said shaft, a pawl carried by the hammer, a lever to swing said pawl into locking engagement 75 with the disk, and means for releasing said pawl from locking engagement with the disk.

4. In a typewriter operating mechanism of the character described, a driven shaft, 80 a toothed disk rigidly secured to said shaft, a key engaging hammer journaled intermediate its ends to said shaft, means for locking the hammer to revolve with the disk, a pivoted spring pressed lever for throwing 85 said means into operative position, a perforated strip to actuate said lever, and means for rendering said first mentioned means inoperative.

In testimony whereof I affix my signature 90 in presence of two witnesses.

WILHELM S. FERNE.
